[57] CLAIM

The ornamental design for a combined drink cup holder and support, as shown and described.

DESCRIPTION

FIG. 1 is a perspective view of a combined drink cup holder and support showing my new design;

FIG. 2 is a side elevational view thereof the opposite being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a side elevational view of an alternate embodiment of FIG. 1, the opposite side being a mirror image;

FIG. 8 is a perspective view of an alternate embodiment of FIG. 1;

FIG. 9 is a side elevational view of FIG. 8, the opposite side being a mirror image;

FIG. 10 is a front elevation view of FIG. 8;

FIG. 11 is a rear elevational view of FIG. 8;

FIG. 12 is a top plan view of FIG. 8;

FIG. 13 is a bottom plan view thereof;

FIG. 14 is a side elevational view of an alternate embodiment of FIG. 1; the opposite side being a mirror image;

FIG. 15 is a side elevational view of an alternate embodiment of FIG. 1, the opposite side being a mirror image; and,

FIG. 16 is a side elevational view of alternate embodiment of FIG. 1, the opposite side being a mirror image. The holder portion of the alternate embodiments are the same as those shown in FIGS. 1-6.
